UNITED STATES PATENT OFFICE

148,522

DESIGN FOR A DOLL SWING

Clyde R. Conger, San Francisco, Calif.

Application August 19, 1946, Serial No. 132,643

Term of patent 7 years

(Cl. D34—15)

To all whom it may concern:

Be it known that I, Clyde R. Conger, a citizen of the United States of America, residing in the city and county of San Francisco and State of California, have invented a new, original, and ornamental Design for a Doll Swing, of which the following is a specification, reference being had to the accompanying drawings, forming part thereof.

Fig. 1 is a front elevation of a doll swing showing my new design;

Fig. 2 is a plan view of the swing, also showing the new design, and

Fig. 3 is a side elevation of the swing, also showing the new design.

I claim:

The ornamental design for a doll swing, substantially as shown.

CLYDE R. CONGER.
